The ornamental design for a removable decorative pleated fabric cover for an airport beverage dispenser, as shown and described.

DESCRIPTION

FIG. 1 is a top and side perspective view of a removable decorative pleated fabric cover for an airport beverage dispenser showing my new design, and shown in functional relationship with an airport illustrated in phantom outline; FIG. 2 is a side view thereof, the unshown opposite side being of identical appearance; and,

FIG. 3 is a top view thereof, the unshown bottom view being of identical appearance.

The broken line showing of an airport beverage dispenser in FIG. 1 is for illustrative purposes only and forms no part of the claimed design.
